UNITED STATES PATENT OFFICE.

HARRY M. REGNIER, OF DECATUR, ILLINOIS.

CLIP FOR HOLDING RAILROAD SIGNAL-TORPEDOES.

1,193,062.

Specification of Letters Patent.

Patented Aug. 1, 1916.

Application filed August 3, 1912. Serial No. 713,144.

To all whom it may concern:

Be it known that I, HARRY M. REGNIER, a citizen of the United States, and a resident of Decatur, in the county of Macon 5 and State of Illinois, have invented certain new and useful Improvements in Clips for Holding Railroad Signal-Torpedoes, of which the following is a specification, reference being had to the accompanying drawings.

This invention relates to improvements in clips for holding railroad signal torpedoes securely in place on the top of a rail.

The object of this invention is to provide 15 an inexpensive spring clip so arranged and constructed that the same can be readily sprung upon a rail head of conventional construction in a manner insuring the torpedo carried by the clip being securely held in 20 position.

With the above and other objects in view, my present invention consists in certain novel features of construction as will be more fully described hereinafter.

25 In the accompanying drawings forming a part of this specification and in which like numerals of reference indicate similar parts in the several views:—Figure 1 is a cross sectional view of a portion of a railway rail 30 showing a torpedo held in position by means of a holder or clip embodying my invention. Fig. 2 is a top view of Fig. 1. Fig. 3 is a plan view of the clip.

Referring particularly to the drawings, 35 10 designates my improved torpedo holding clip which is constructed from a single length of spring wire bent to form the straight base stem or member 11, having at its ends two oppositely positioned flattened 40 or oblong loops 12. These loops extend in parallel spaced relation. After forming the loops 12, the wire is continued downwardly to form the crooked rail head engaging arms 13 which conform to the shape of the sides 45 of the head of the rail. After forming the crooked rail head engaging arms 13, the ends of the wire are extended inwardly and downwardly to form the rail gripping ends 14, the curved extremities 15 of which fit 50 closely against and firmly grip the opposite sides of the web 16 of the rail as clearly shown in Figs. 1 and 2.

When engaged with the rail in the manner described, the stem or base member 11 of the clip is disposed diagonally across the 55 top of the tread 17 of the rail as shown.

An especially crimped torpedo 21 is used in connection with this clip the ends 15 of which are adapted to fit into the loops 12.

From the foregoing description taken in 60 connection with accompanying drawings the construction and operation of the invention will be readily understood and it will be seen that a torpedo may be quickly and firmly secured to the rail in such a manner 65 as to prevent its being casually dislodged or removed by a jar or otherwise, until exploded by a moving wheel or removed by direct human agency.

I am aware that prior to my invention, 70 railroad signal torpedoes have been made with flexible or spring clips or straps and metallic, fiber or paper cases, and I therefore do not claim such combination broadly.

There is a special advantage in constructing 75 the wire member as shown in that the end 15 enables the wire loop to be hooked over the torpedo body when not in use. These ends 15, formed at the correct angle and degree of curve will hook perfectly over 80 the stem 11 or the torpedo body, making the clip torpedo compact for shipping, prevents tangling and makes it possible to hook and lock torpedoes on lantern frames or other tools, when carried by trainmen.

Having thus described my said invention, what I claim as new and desire to secure by 85 United States Letters Patent is:—

A clip of the character described comprising a spring member made of a single 90 length of spring wire including a base stem having at each end an oblong loop said loops extending in parallel spaced relation and arranged to lie on top of a rail from each of which is continued a crooked rail head 95 engaging arm each arm ending in a curved extremity adapted to lie against the web of a rail, as and in the manner set forth.

In testimony whereof I affix my signature, in presence of two witnesses.

HARRY M. REGNIER.

Witnesses:

MARY E. BEAN,
N. D. PORTER.
